UNITED STATES PATENT OFFICE.

ASA D. SANDS, OF CAMDEN, NEW JERSEY.

RECEPTACLE PLATE FOR ELECTRICAL OUTLETS.

Application filed November 29, 1920. Serial No. 426,999.

To all whom it may concern:

Be it known that I, ASA D. SANDS, a citizen of the United States, residing at Camden, in the county of Camden and State of New Jersey, have invented new and useful Improvements in Receptacle Plates for Electrical Outlets, of which the following is a specification.

My invention relates to new and useful improvements in receptacle plates for electrical outlets, and has for its object to provide such a plate with an adjustable door whereby said door may be positioned to suit conditions or desires of the user regardless of the position of the receptacle plate.

Another object of the invention is to provide an adjustable door holding member, arcuate in shape, and to which a door is hinged in any suitable manner, whereby the door and its holding member may be adjusted to open upwardly regardless of the position of the receptacle plate or to open in any other direction.

A further object of the invention is to provide a stop for said door formed from the door holding member.

A still further object of the invention is to provide the edge of the receptacle plate surrounding the door opening with a circumferential groove in which sets the door holding member, so as to be rotatable therein, said holding member having the ends of a pintle attached thereto, to which the door is connected or hinged.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:

Fig. 1, is a face view of one form of a receptacle plate illustrating the application of my invention.

Fig. 2, is a section at the line 2—2 of Fig. 1.

Fig. 3, is a reverse face or back view of the door holding member with the door therein.

Fig. 4, is a similar view of the door holding member.

Fig. 5, is a similar view of the door.

Fig. 6, is a view similar to Fig. 1 of a different formation.

Fig. 7, is a section at the line 7— of Fig. 6.

Fig. 8, is a section of the door holding member at right angles to Fig. 7.

Fig. 9, is a bottom or inner plan view thereof.

In carrying out my invention as here embodied, 2 represents a receptacle plate for electrical outlets which may be of any desirable shape, size and construction for use with single and multiple outlets or connections. In the plate here illustrated is an outlet opening 3 circular in shape and in the edge of the plate surrounding said opening is formed a circumferential groove 4 preferably V-shaped in cross section as plainly shown in Fig. 2.

The reference numeral 5 denotes the door holding member, arcuate in shape and having a central door opening 6 in other words, the door holding member is in the form of a ring section or split ring, the ends of which are spaced apart as shown in Fig. 4 and the outer edge of said door holding member is beveled to fit the groove 4.

In the reverse face or back of the holding member at the ends thereof are formed the aligning pintle grooves 7 in which rest the ends of the pintle 8, said pintle being held in place by swaging the metal about the pintle as at 9 or in any other suitable and well known manner.

The door 10 is shaped to fit within the door opening 6 and between the shaped ends of the door holding member 5, the reverse face or back of said door having a pintle 11 across the extension 12 of the door or the part thereof lying between the ends of the door holding member and this groove registers with or receives the central portion of the pintle to which said door is held by swaging the metal about the pintle as at 13, Figs. 2 and 3, and this last mentioned swaging does not firmly engage the pintle so that the door can swing upon said pintle. To prevent the door swinging inward beyond the holding member I provide a stop 14 which is formed by swaging a lip from the inner edge of the door holding member and this leaves a recess or space for the insertion of the thumb nail to open the door.

The plate 2 is provided with holes 15

for the passage of fastening means such as screw for fastening the same to a wall and may also be provided with other holes for other purposes as for holding push buttons.

5 In practice the door holding member 5 is inserted in the outlet opening 3, without the door, by forcing the ends of the holding member together until the edge thereof will pass into the opening 3, then by releasing the pressure on said holding member the same will spring into the groove 4, then the door 10 with the pintle 8 may be attached to the holding member as hereinbefore described.

15 In Figs. 6 to 9 inclusive, I have shown the door holding member of different construction designated by the numeral 25 formed from a channel ring-section thereby producing flanges 26 and 27 which include 20 the outer or inner faces respectively of the receptacle plate 2 when said door holding member is placed in the outlet opening 3, said outlet opening in this case not having the groove 4 above referred to. The door 25 10 with its extension 11 carrying the pintle 8 fits within the door holding member and the projecting ends of the pintle enter the channel of the door holding member at the spaced ends thereof wherein they are held 30 by the crimping of the flanges of the door holding member about the projecting ends of the pintle as plainly shown in Fig. 7. To prevent the door swinging inward beyond the holding member I form a stop 35 28 by partially cutting a section of the metal from the inner flange 27 and bending the same back until it projects into the door opening formed within the door holding member as shown in Fig. 7.

40 In use the plate may be installed in any position and the door positioned to swing

open in any desired direction by rotating the door holding member the proper distance within the outlet opening where it will remain due to the friction between said 45 holding member and the plate in which it is mounted.

Of course I do not wish to be limited to the exact details of construction as herein shown as these may be varied within the 50 limits of the appended claims without departing from the spirit of my invention.

Having thus fully described my invention, what I claim as new and useful is:—

1. A receptacle plate for electrical outlets comprising a plate having an outlet opening and provided with a circumferential V-shaped groove, a door holding member having its edge rotatably mounted in said groove and a door hinged to said holding member. 55

2. In a device of the character stated, a metal door holding member having a central opening and its ends being spaced apart, a door stop at the inner edge of said member formed by swaging a portion of the metal therefrom, the ends of said member having aligning grooves, a door for closing the opening in said member, said door having a groove therein, a pintle in said grooves and 60 means for attaching the pintle to the parts. 65

3. In a device of the character stated, a plate having an outlet opening the edge of said plate about said opening having a V-shaped circumferential groove therein, an 70 arcuate door holding member, the edges of which are beveled for registration with the V shaped groove and a door hinged to said member. 75

In testimony whereof, I have hereunto af- 80 fixed my signature.

ASA D. SANDS,
